UNITED STATES PATENT OFFICE

ISAAC SLATER CALL, OF SAVANNAH, GEORGIA

FILING CABINET

Application filed March 25, 1929. Serial No. 349,819.

The object of the present invention is to provide a simple and effective means for storing deposit slips or vouchers used in "Christmas Club" savings accounts, such means eliminating much bookkeeping and simplifying bank operations, while maintaining a complete and very readily accessible record and check upon each account.

In the drawings:

10 Figure 1 is a perspective view of a filing cabinet embodying the present invention.

15 Figure 4 is a horizontal sectional view on the line 4—4 of Figure 3.

20 Figure 6 is a perspective view of a holder for a modified form of deposit slip.

25 In the preferred embodiment of the invention a case is employed, designated 9, in which are one or more drawers 10. These drawers hold a plurality of independent containers, designated generally by the reference numeral 11.

The containers are of box-like form, and located in rows, so that they can be turned from a rearwardly to a forwardly inclined position, as will be evident. Each of the containers is preferably made of a sheet of relatively heavy paper, and comprises a rear wall 12, a front wall 13, a side wall 14, and a bottom 15. The side opposite the side wall 14 is preferably open, as is also the top. The 30 rear wall extends well above the front wall, forming an identifying tab 16 which may be suitably numbered as indicated at 17, and ruled as at 18 to receive the name and address of the depositor. The front wall 13 has the 35 portion adjacent to the open side cut away as shown at 19, this cut-away portion extending to a point in proximity to the bottom 15 and leaving a small upstanding retaining flange 20. At its upper corner it is further cut away as shown at 21.

The records to be filed in this cabinet are preferably the deposit slips for "Christmas Club" savings and the like. As illustrated in Figure 7, the depositor is provided with a book 22 of detachable slips or coupons, each carrying a specific number 23 and each being numbered successively as illustrated at 24, these two latter numbers being on the upper ends of the slips or leaves. The amount to be paid at predetermined periods is shown 40 at 25, and the total amount paid to the day of each period is illustrated at 26. It will be observed that these amounts 25 and 26 are located on the right-hand side of each slip and that a blank space 27 is provided at 45 the left hand to receive the said stamp acknowledging that all previous payments have been made as illustrated at 28 in Figure 7.

In utilizing the structure constituting the invention, when a depositor makes a payment, the slip or leaf for that payment is detached from the book 22 and the succeeding leaf is then stamped as shown at 28. The depositor passes to the receiving teller the 50 detached slip with the payment made. The receiving teller has only to locate the particular container and place therein the deposit slip. As these slips accumulate each therefore has the complete records of all deposits made and which have been stamped. The depositor on the other hand retains the book and on the outer sheet or slip thereof is shown the receipt stamp. Obviously the various 55 accounts can be quickly ascertained by reason of the upstanding tabs 16 and any one account can be easily determined because the outermost sheet has sufficient of the data thereon exposed to show the amount of the last payment. The open side and end of the container permits the ready insertion of the 60 slips and the front open portion not only exposes the payments made, but it permits the upper right-hand corners to be turned back so that each successive numbering 24 on the slips can be quickly determined.

The same apparatus is usable for various types of accounts. Thus in Figure 6 there is shown a modified form of leaf in which selective amounts 29 can be determined by punching at appropriately indicated points 30 any 65 70 75 80 85 90 95 100 105 110 115 120 one or more selected sums to be periodically paid. As will be noted by reference to Figure 6 the cut-away portion 19 of the container exposes not only the various amounts but those selected by punching as at 31.

5 From the foregoing, it is thought that the construction, operation and many advantages of the herein described invention will be apparent to those skilled in the art without further description and it will be understood that 10 various changes in the size, shape, proportion and minor details of construction may be resorted to without departing from the spirit or sacrificing any of the advantages of the 15 invention.

15 What I claim, is:

1. A filing cabinet of the character set forth, comprising a casing, a drawer therein, and a row of box-like containers located in 20 the drawer and adapted to be tilted between a forward and rearward inclination therein, each of said containers consisting of a box-like structure for receiving a plurality of slips and having a bottom, a front wall and 25 one side wall, the other side being open and the front wall at the open side being cut away to a point in proximity to the bottom, the top of each container being open and the rear wall extending to a point above the front 30 wall, forming an identifying tab.

2. A filing cabinet of the character set forth, comprising a holder and a plurality of card containers movably mounted therein and each having an open top, a rear wall and a 35 front wall that is shorter than the rear wall and is also cut away along one side to a point in proximity to the bottom, said rear wall and front wall being connected at the side opposite to that side of the front wall which is cut 40 away.

In testimony whereof, I affix my signature.
